DESIGN FOR AN ELECTRIC FENCE ENERGIZER

Lorell J. Schilling, Chicago, Ill., assignor to Bab-
son Bros. Co., a corporation of Illinois

Application November 22, 1943, Serial No. 111,765

Term of patent 14 years

To all whom it may concern:

Be it known that I, Lorell J. Schilling, a citizen
of the United States, residing at Downers Grove,
in the county of Du Page and State of Illinois,
have invented a new, original, and ornamental
Design for an Electric Fence Energizer, of which
the following is a specification:

Figure 1 is a front elevational view of an elec-
tric fence energizer, showing my new design;

Figure 2 is a bottom view of the same device;
Figure 3 is a side elevational view, from the left
of Figure 1; and

Figure 4 is a plan view of the electric fence
energizer.

I claim:

The ornamental design for an electric fence
energizer, as shown.

LORELL J. SCHILLING.
